[57] CLAIM

The ornamental design for a vehicle body, as shown and described.

DESCRIPTION

FIG. 1 is a front perspective view of a vehicle body showing our new design;

FIG. 2 is a rear perspective view thereof;

FIG. 3 is a left side view thereof, it being understood that the side opposite to that shown is a substantial mirror image thereof;

FIG. 4 is a front view thereof; and,

FIG. 5 is a rear view thereof.

It will be understood that the broken line showing throughout the drawings is for illustrative purposes only and forms no part of the subject design.
